US00D953159S

(12) **United States Design Patent** (10) **Patent No.:** **US D953,159 S**
Wetterström et al. (45) **Date of Patent:** **** May 31, 2022**

(54) **PACKAGE**

(71) Applicant: **DENTSPLY IH AB**, Mölndal (SE)

(72) Inventors: **Sophia Wetterström**, Hjälteby (SE); **Anders Eliasson**, Stockholm (SE); **Julian Stubbs**, Stockholm (SE); **Robert England**, Stockholm (SE); **Christian Grönlund**, Sävedalen (SE); **Susanne Lindholm**, Lindome (SE); **Frida Iselau**, Landvetter (SE); **Thomas Nyberg**, Skummeslövsstrand (SE); **Eric Hummel**, Gothenburg (SE); **Khantipol Kasemsant**, Samutprakarn (TH)

(73) Assignee: **DENTSPLY IH AB**, Mölndal (SE)

(**) Term: **15 Years**

(21) Appl. No.: **29/726,327**

(22) Filed: **Mar. 2, 2020**

(30) **Foreign Application Priority Data**

Aug. 29, 2019 (EM) 006785622
